[57] CLAIM

The ornamental design for a hand-held resilient exercise block, as shown and described.

DESCRIPTION

FIG. 1 is a top plan view of a hand-held resilient exercise block showing my new design, the bottom plan view being identical;

FIG. 2 is a side elevational view thereof, both sides being identical;

FIG. 3 is a front elevational view thereof, the rear elevational view being identical;

FIG. 4 is a cross-sectional view thereof taken along line 4—4 of FIG. 1; and

FIG. 5 is a cross-sectional view thereof taken along line 5—5 of FIG. 1.

FIG. 1

FIG. 2

FIG. 3

FIG. 4

FIG. 5
